UNITED STATES PATENT OFFICE.

FRED P. ANGELL, OF BATTLE CREEK, MICHIGAN.

AIR-CONTROLLED-PISTON DOOR-CHECK.

1,359,144.

Specification of Letters Patent. Patented Nov. 16, 1920.

Application filed May 1, 1920. Serial No. 378,101.

To all whom it may concern:

Be it known that I, FRED P. ANGELL, a citizen of the United States, residing at the city of Battle Creek, county of Calhoun, and 5 State of Michigan, have invented certain new and useful Improvements in Air-Controlled-Piston Door-Checks, of which the following is a specification.

This invention relates to improvements in 10 air controlled piston door checks.

The objects of the invention are,

First, to provide an effective cylinder and piston structure.

Second, to provide an improved gear 15 structure which shall be variable in its action to secure the desired result.

Further objects and objects relating to details and economies of operation and construction will definitely appear from the 20 detailed description to follow.

I accomplish the objects of my invention by the devices and means described in the following specifications. The invention is clearly defined and pointed out in the claims.

25 Structures which are preferred embodiments of my invention are clearly illustrated in the accompanying drawings, forming part of this specification, in which:

Figure I is a perspective view of my improved door check in position on a door with the door closed.

Fig. II is a similar perspective with the door open.

Fig. III is a detail view, somewhat enlarged, with parts broken away.

Fig. IV is an enlarged detail sectional view through the piston, rack, gear and guide means for the rack, taken on line 4—4 of Figs III and V, showing the valve 40 closed.

Fig. IV^a is a detail view showing the valve open.

Fig. V is a detail sectional view on line 5—5 of Fig. IV.

45 Fig. VI is a detail sectional view on line 6—6 of Fig. VIII, showing the arrangement of the expansion spring within the cup packing.

Fig. VII is a detail sectional view on line 50 7—7 of Figs. I and III showing details of the control valve.

Fig. VIII is a detail sectional view similar to Fig. IV, showing a modification of the piston and valve.

55 In the drawings the sectional views are taken looking in the direction of the little

arrows at the ends of the section lines, and similar numerals of reference refer to similar parts throughout the several views.

Referring to the numbered parts of the drawing, 1 is the cylinder of my improved door check, provided with a rear head 2 and a head 3 containing the gearing connections. These are secured to the door by suitable clip pieces 4, 4, seen in Figs. I, II and III. 60 Arm 5 is connected to the actuating part and is connected by link 6 to a clip 7 on the door casing above the door. Such arm and link connections being common expedients with door checks, they are not detailed here. 65

The arm 5 is carried by the vertical rock shaft 8, which carries upon it the cam shaped gear 9, which is geared to actuate the divided head 10, 10'. The head 10 is provided with a hollow stem or rod 11 disposed within the reciprocating member or rack bar 12, which is provided with rack teeth 13 corresponding to the cam shaped gear 9. The rack bar 12 is guided by engagement with the reduced portion of the head 3. 70

The piston head 10 is provided with a leather cup-shaped packing 14, which is retained in place by a washer 15, as seen in Figs. IV and VIII. The cup-shaped packing is expanded and forced against the walls 85 of the cylinder by the expansion spring rings 16 (see Figs. IV, VI and VIII) which expands snugly within the packing and brings it into close contact with the walls of the cylinder 1.

The stem 11 is open at 17 through into the cylinder and fits against a suitable gasket 18, and an inlet opening 19 is provided in bar 12 to deliver air through the same. 90

The head 4 of the cylinder is perforated at 20 with a small aperture, the size of which is regulated by the pointed screw 21 (see Fig. VII), so that the escape of the air from the cylinder can be very nicely regulated by merely adjusting the screw 21. 95

In Fig. VIII, I show a modification of the piston construction. This consists of a head 22 carried by a yoke 23 on the rack bar 12. The piston is perforated at 24 and provided with a surrounding valve seat 25, and a sole leather valve 26 is provided to seat against this valve seat. The valve is drawn securely to place by the coil spring 27 secured thereto and attached to the eye 28 within the yoke 23. 105

The piston in either structure is urged toward its head by means of the spring 29. 110

With my improved door check in place when the door is open the arm 5 is swung, and through its connection to the rock shaft 8 acts upon the cam shaped gear 9, which 5 moves the irregular rack bar 12 carrying the piston from the bottom of the cylinder and air enters through the valved opening in the piston.

When the door is released and allowed to 10 close, the spring 29 reacts upon the piston and closes the air opening, confining the air within the cylinder and compressing the same, as shown. This swings the door shut at a rapid rate, because the spring acts on 15 the short radius of the gear. The door will be checked before it closes because of the resistance of the air compressed within the cylinder. The spring, however, tends to further close the door, and the air gradually escapes through the restricted aperture 20. When the air escapes, because the rack is acting on the gears of the longer radius, it very readily and easily closes the door by a slow moving strong pressure.

25 The structure I have shown in Fig. IV is very positive in its action and highly effective, but the structure illustrated in Fig. VIII is also effective and much more economical to produce.

30 It is of the highest consequence to completely confine the air so as to insure its resistance until released through the regulated aperture.

Having thus described my invention, what 35 I claim as new and desire to secure by Letters Patent, is:

1. In a door check the combination of a suitable cylinder, with a restricted regulated discharge opening at the head thereof, 40 a piston therein with a cupped leather pack-

ing, an expansion spring ring within the cupped packing to close the same into close contact with the cylinder walls, a cam shaped pinion disposed in the opposite end of said cylinder, on an axis transverse to the 45 cylinder an irregular rack bar meshing with said pinion and guided on the head and connected to the said piston, a spring within the cylinder arranged to urge the piston into the said cylinder, a valved opening through the 50 said piston head comprising a stem on the said piston entering a recess in said rack bar, with a valved opening at the end thereof, stop means to limit the opening of the said valve, coacting for the purpose specified.

2. In a door check the combination of a suitable cylinder, with a restricted regulated discharge opening at the head thereof, a piston therein with a cupped leather packing, 60 an expansion spring ring within the cupped packing to close the same into close contact with the cylinder walls, a cam shaped pinion disposed in the opposite end of said cylinder, on an axis transverse to the cylinder an 65 irregular rack bar meshing with said pinion and guided on the head and connected to the said piston, a spring within the cylinder arranged to urge the piston into the said cylinder, and a valved opening in the piston 70 head to admit air as the piston is withdrawn, coacting for the purpose specified.

In witness whereof I have hereunto set my hand and seal in the presence of two witnesses.

FRED P. ANGELL. [L. S.]
